TOY BOMB

Charles E. Buxton, Pleasant Hill, Mo.

Application April 9, 1951, Serial No. 220,021

1 Claim. (Cl. 46—200)

1

This invention relates to improvements in toys and more particularly to a toy bomb.

The principal object of the present invention is to provide a toy in the form of an aerial bomb, in which an explosive cap may be conveniently placed and detonated when the bomb has been thrown and strikes headfirst an object.

Another object of the invention is to provide a toy bomb of simple construction and capable of being retailed at a low monetary figure.

Still another object of the invention is to provide a bomb having a special head structure which will remain intact until it strikes some solid object, whereupon it will exert force against an explosive cap to cause the discharge thereof.

A further object of the invention is to provide a toy bomb of the character stated which is of durable construction and not susceptible to the ready development of defects.

These and various other objects and advantages of the invention will become apparent to the reader of the following description.

In the drawing:

Figure 1 is a side elevational view of the toy;

Figure 2 is a tail end elevational view of the toy;

Figure 3 is a longitudinal sectional view, through the device;

Figure 4 is a cross section taken on line 4—4 of Figure 3;

Figure 5 is a cross section taken on line 5—5 of Figure 3;

Figure 6 is a fragmentary perspective view of the forward end of the body;

Figure 7 is a perspective view of the head.

Referring to the drawing, wherein like numerals designate like parts, it can be seen that numeral 5 denotes an elongated tapered body, this being of substantially frusto-conical shape, the smaller end being formed with cross slots 6 to receive a pair of tail structures 7, each tail structure being of angular formation and disposed into the slots snugly, so as to define four fins, as is clearly shown in Figure 2.

The other, or larger end of the body 5 has a firing chamber 8. This chamber is of cylindrical shape and is adapted to receive the plunger projection 9 of a hemispherical-shaped head 10. The plunger projection 9 is preferably flared slightly toward its free end and is formed with intersecting slots 11, extending inwardly to define four flexible legs 12, and the central solid core 13, there being a firing pin head 14 exposed on the free end of the core 13, as is apparent in Figure 7.

2

The projection 9, being slightly flared, permits the fingers 12 to flex inwardly, when the projection 9 is forced into the firing chamber 8, the fingers frictionally engaging the inside of this end portion of the body and holding the head 10 against displacement from the body 5.

A plurality of angularly bored discharge or spit openings 15 are formed in the body 5 and extend backwardly from the head 10, from the firing chamber 8, this so that when a cap is exploded in the chamber 8, the products of explosion will take a backward course out of the chamber 8, so that surfaces against which the explosive spray may hit, will not be marred.

The inner wall of the chamber 8, has a recess 16, which receives a firing pin, having a head 17.

At this point, it might be understood, that the construction of the toy, may be reversed, in that the head 10, may have the firing chamber 8, and the body 5, provided with the projection 9, without departing from the spirit and scope of the invention.

In the use and operation of this toy, the head 10 is first removed from the body 5, and holding the toy with the larger end of the body 5, upright, an explosive cap is placed in the chamber 8, and against the firing pin head 17.

The projection 9 of the head 10 is now inserted into the chamber 8 and pressed inwardly until the firing pin head 14 engages the cap (not shown).

The toy may now be thrown and the heavier end, being the head 10, will first strike an object, with the result that the cap is pressed by force 35 between the pin heads 14, 17, and thus discharged or detonated. The products of the detonation emanate through the spit openings 15, and these openings being disposed rearwardly, will not give the products of explosion any opportunity to mar adjacent forward surfaces of the objects against which the bomb hits.

While the foregoing description sets forth the invention in specific terms, it is to be understood that numerous changes in the shape, size and materials may be resorted to, without departing from the spirit and scope of the invention as claimed hereinafter.

Having described the invention, what is claimed as new is:

A device of the character described comprising an elongated body, said body having a cylindrical firing chamber centrally disposed in its inner end, a head portion, a centrally disposed projection of square cross sectional area formed 50 integrally with said head, a plurality of flexible

fingers affixed to the head and each extending in spaced parallel relation to the sides of said projection and in spaced circumferential relation to each other, said fingers each having rounded outer faces frictionally and slidably engageable with the wall of said firing chamber, a firing pin centrally affixed in the inner end of said firing chamber, and a firing pin head centrally affixed to the free end of said projection.

CHARLES E. BUXTON.
